MOTOR OPERATED WINCH UNIT

Victor H. Mathieu, Minneapolis, Minn., assignor to
M.K.S. Winch, Inc., Minneapolis, Minn., a corpora-
tion of Minnesota

Filed July 7, 1958, Ser. No. 51,720

Term of patent 14 years

(Cl. D41—1)

Fig. 1 is a front elevational view of a motor operated winch unit showing my new design, the rear being substantially the same as the front shown;

Fig. 2 is a top plan view thereof;

Fig. 3 is a left end elevational view thereof; and
Fig. 4 is a right end elevational view thereof.

I claim:

The ornamental design for a motor operated winch unit, as shown and described.
